Application July 24, 1937, Serial No. 155,381
In Japan August 1, 1936

2 Claims. (Cl. 9—1)

A rubber cylinder may be given a desired shape if filled with air, but if it receives pressure, it has the drawback of being unable to resist the pressure and changing its shape. Accordingly, it in that condition cannot be used as a water ski or boat which receives big pressure.

The present invention relates to a water ski and boat, which consists in forming a pair of sliding bodies by connecting several rubber cylinders in parallel, fixing a tubular rod to the bottom surface of each of said rubber cylinders so that the center of gravity may be at the bottom of the rubber cylinder and attaching a flat member, which serves as a pedal, to the face of each 15 of said sliding bodies and connecting said pedal to a tubular rod connecting piece, said pair of sliding bodies being provided at the center with a seat which can rise or fall or be detached freely so that a boat may be obtained by lifting or 20 attaching the seat and also raising an oar supporter hinged to the pedal; or that a ski may be had by laying down or detaching the seat and also loosening the connection between two pairs of the sliding bodies so as to be able to move alternately.

According to this invention, the rubber cylinder is kept from inclining or overturning during running or sailing by stabilizing its buoyancy with a tubular rod and moreover is given a resistance to pressure so that it is free from the apprehension of changing its shape under pressure during running. Further, as in transportation it is possible to separate it from the tubular rod and exhaust air from it and separate 35 the tubular rod from the connecting member, it is very convenient to carry and may be used as a boat or ski in spite of the floating body being made of rubber.

Referring to the accompanying drawing which 40 shows one embodiment of this invention,

Figure 1 is a cross section of the water ski and boat according to the present invention with the seat raised and partly cut off;

Figure 2, a plan of the same with the seat 45 raised and

Figure 3, a side view.

In the drawing, 1 is a rubber tube having inserted therein an inner bag 2 to be filled with air.

At the bottom of a rubber cylinder 1 is provided a tubular rod 3 which has a desired length and is connected to the above bottom by means of a connecting ring 12. The rubber cylinders 1 are arranged in parallel by twos and a flat member 4 serving as a pedal is disposed on the upper surface of their center. To the lower side

of said pedal is fixed the upper central part of a tubular rod connecting piece 5, the lower portions of which spread outwardly with their ends forming rings 15 to hold the tubular rods and thus fix them to the rubber cylinders 1 so that the center of gravity may be at the bottom of the cylinder 1. Also, the rubber cylinder 1, the rear end and the parts slightly above and below the center of the tubular rod 3 are connected together by the connecting piece 5, the rubber cylinder 1 having a tapered end and a sliding body being formed by joining two such rubber cylinders 1 with their ends united and inserted into a metal shce 16. At the pedal 4 or the upper portion of the connecting piece there is provided 15 a joining piece, for example, a hinge 17 to which to hinge one ends of the arms 6, 7 and 9, 10 which can rise and fall freely, the arms 6 and 7 being raised and joined and the tubular portion 18 being fitted in their joined ends. If the arms 6 20 and 9 are inclined as indicated in Figures 1 and 2, they embrace the rubber cylinders while the arms 9 and 10 are raised to form a supporter for an oar 11 and are fitted at their ends with racks for the oar 11. 19 is a supporter secured to each of 25 the tubular rods 3, 3 and has a link 20 hinged to the upper face of its center so as to enable each pair of the rubber cylinders 1, 1 to move alternately when a water ski is wanted.

12 and 13 are engaging pieces whose ends are 30 connected respectively with the front sides of the pedal 4 and a tubular rod 5 in such a manner as can rise and fall freely. They keep the foot from slipping when raised upward. 21 is a heel piece.

In this invention, since a tubular rod is provided at the center of the lower part of the rubber cylinder, its gravity against the buoyancy of the cylinder makes an inverted triangle and accordingly does not only maintain the cylinder in 40 a stable condition, but keeps it from inclining or overturning. Moreover, this article can not only move straight towards the running or sailing direction, but may be folded if air is exhausted from the rubber cylinder. Also, the tubular rod 3 may be separated from the connecting member and the tubular rod connecting piece 5 be removed from the rubber tubular rod. This makes it convenient to carry and transport. Besides, it 45 can be used as a boat or ski if each pair of the arms which can rise and fall is raised and is fitted with a seat or is made to support an oar. Again, by inclining said arm the rubber cylinder may be held. Also, this boat may be reconstructed into 50 55

a ski. It has the further advantage of being easily assembled or taken to pieces.

I claim:

- 5 1. A device of the character described, comprising a series of metallic members of approximately H-shape, each leg thereof being shaped to form the arc of a circle with a ring-shaped extension disposed below the center of said arc, a tubular rod secured in the ring-shaped extensions of each leg and connecting said metallic members together in spaced alinement, a pair of flexible cylinders, and means to support the same in laterally spaced parallel relation in the arc-shaped portions.
- 10 10. signs of each leg and connecting said metallic members together in spaced alinement, a pair of flexible cylinders, and means to support the same in laterally spaced parallel relation in the arc-shaped portions.

2. A device of the character described, comprising a series of metallic members of approximately H-shape, each leg thereof being shaped to form the arc of a circle with a ring-shaped extension disposed below the center of said arc, a tubular rod secured in the ring-shaped extensions of each leg and connecting said metallic members together in spaced alinement, a pair of flexible cylinders, means to support the same in laterally spaced parallel relation in the arc-shaped portions, and means for rigidly connecting a second set of metallic members in parallel spaced relation with said first series.
